UNITED STATES PATENT OFFICE

115,030

DESIGN FOR A CIGARETTE CASE OR SIMILAR ARTICLE

Norman Edwards, New York, N. Y., assignor to Paul E. Plato, New York, N. Y.

Application March 22, 1939, Serial No. 83,748

Term of patent 3½ years

To all whom it may concern:

Be it known that Norman Edwards, a citizen of the United States and resident of New York city, in the county of New York and State of New York, has invented a new, original, and ornamental Design for a Cigarette Case or Similar Article, of which the following is a specification, reference being had to the accompanying drawing, forming part thereof, in which,

Fig. 1 is a perspective view of a cigarette case embodying my new design.

Fig. 2 is an end elevational view of the left hand end thereof, and

Fig. 3 is a rear elevational view thereof.

I claim:

The ornamental design for a cigarette case or similar article, substantially as shown.

NORMAN EDWARDS.
